In Germany February 18, 1935

8 Claims. (Cl. 179—17)

This invention relates in general to improvements in telephone systems but more particularly to systems in which a plurality of lines are connected through a junction point to a plurality of call routes by way of a common connecting line. A calling line is thus connected with the associated outgoing line by means of the junction. The present invention relates to the control of the junction point and is characterized in that the control means of the junction point are influenced simultaneously with the establishment of the call route over connecting devices of the exchange in a manner which corresponds to the calling line. By effecting the switching over at the junction only when the call route over the connecting devices has been established the control devices at the switching over point can be constructed in a manner which is particularly favorable to the efficiency of an arrangement of this sort in comparison with arrangements in which the switching over operation at the junction takes place at some other time. It is moreover possible to dispense with special switching over relays at the junction point. Dispensing with special switching means in this way has, in addition to the very great technical advantage that the number of contacts in the speaking lines is reduced to a minimum and switching means which might for example cause distortion of the impulses are rendered completely unnecessary.

The invention is illustrated in connection with so-called two-party connections in which two subscribers' stations whose lines are brought together at a common switching point are connected at the switching point (USt2) over a common connecting line VL. The invention is, however, not limited to two-party line systems, it is equally possible for more than two subscribers' lines to be associated at the switching-over point (USt1) and furthermore, instead of subscribers' stations, connecting lines, party lines or the like may be connected up.

In the drawings Fig. 1 shows a circuit arrangement of an embodiment of the invention, while Fig. 2 is a modification thereof.

In the drawings two subscribers' stations TSt1, TSt2 are shown, whose lines are brought to the switching-over point USt1 and are connected to the common connecting line VL. This connecting line leads by way of the switching-over point USt2 to the exchange connection in which one approach to an individual preselecting device is provided for each subscriber of the two-party line system. Although in the embodiments the preselecting devices are represented by call

finders the invention is not limited to these. It is moreover not necessary for both the subscribers' stations to be connected to different groups of preselecting devices. It is possible to lead the approach lines to the same group of call finders so that the two approaches are connected to different contacts of the call finder. In the embodiments the general plan in respect of two call finders (AS1 and AS2) is represented. Interconnection between the two subscribers of the two-party line is not possible. The main construction of the arrangements shown in the two embodiments is the same. In Fig. 1, however, a special auxiliary relay is provided at the switching-over point USt2 which controls the switching over of the junction at this point, while in Fig. 2 the control of the junction is effected by a relay provided for the individual lines in the call finder.

The switching operations according to the arrangement in Fig. 1 will first be described.

When the subscriber at station TSt1, for example, takes up his receiver the following circuit is established for relay R1 in the call finder AS1; earth, winding I of relay R1, battery, contact 1t1, resistance Wi1, contact 2c2, a-lead of the connecting line, winding I of relay U1, contact 3u2, subscriber's station TSt1, contact 4u2, winding II of relay U1, contact 5u1, and earth. On account of the resistance W31 in this circuit relay U1 at the switching-over point USt1 does not energize. Relay R1 at the call finder is, however, energized and by closing its contacts 6r1 causes the call finder AS1 to be started up over the start lead AN and contact 1t1 which is in the rest position. The testing circuit for relay T1 of the call finder is prepared over contact 8r1 and 9r1. When the call finder tests on the calling line relay T1 energizes and brings the call finder to rest in the known way: earth in the group selector, c-wiper of the call finder AS1, contact 8r1, winding II of relay R1, contact 9r1 or 10t1, winding II of relay T1, battery, earth. At the same time as relay T1 energizes relay C1 is energized over contact 11c2 when the call finder tests on the calling line. Relay C1 is locked energized over its contact 12c1 and the high resistance Wi2. The energizing of relay C1 effects the switching-over of the connecting line VL on to the connecting path established through the call finder AS1 since contact 13c1 is now open and contact 14c1 is closed. Moreover the high resistance Wi1 in the a-lead of the speaking line is short-circuited by means of contact 15c1 so that the potential which is connected up in the group selector operates in full force on the relay U1 at the switching-over point

USt1. Relay U1 is accordingly energized: earth, battery, relay A1, winding I in the group selector, a-wiper of the call finder AS1, resistance W1, contact 2c2, a-lead of the connecting line, winding I of relay U1, contact 3u2 of the subscriber's station TSt1, contact 4u2, winding II of relay U1, contact 5u1, earth. Relay U1 energizes and closes contact 16u1 thus completing the loop to the group selector. Relay U1 remains energized 10 in this loop until the release of the connection.

Relay C1 moreover serves to characterize the approach for subscriber TSt2 at the final selector as engaged by connecting earth potential over contact 17c1. Relay C1 holds up over resistance 15 W2 until the release of the connection. Windings II of relay R1 and T1 are connected in parallel with relay C1 so that the current then flowing over the relay C1 is no longer sufficient to maintain the latter relay energized. Relay 20 C1 releases and by switching over its contacts 12c1, 13c1, 15c1 and 17c1 returns the system to normal.

The corresponding switching operations occur if station TSt2 initiates a call when the connecting line VL is disengaged. If, however, the connecting line is already engaged on account of the call set up by station TSt1, the station TSt2 is completely disconnected from the connecting line by the opening of contacts 18u1 and 19u1 so that 30 no disturbance of the existing call can occur.

In the case of incoming calls ringing current is connected either to the a-lead or to the b-lead of the connecting line according to the setting of the final selector and the bell of the particular 35 station desired is operated over one lead of the connecting line and earth. At the same time the corresponding relay (C1 or C2) is energized over the c-lead and effects the switching over of the junction at the switching-over point USt2. The further switching operations at the switching-over point USt2 then correspond to the operations occurring in the case of an outgoing call.

The manner of operation of the arrangement as shown in Fig. 2 will now be described. If the subscriber for example at station TSt1 wishes to 45 initiate a call he takes up his receiver and thereby closes a circuit for relay R1 in the call finder AS1: earth, battery, winding I of relay R1, contact 1t1, 2t2, a-lead of the connecting line VL, winding I of relay U1, contact 3u2, subscriber's station TSt1, contact 4u2, winding I of relay U1, contact 5u1 and earth. Relay U1 does not energize since it is in series with the high resistance winding of relay R1 in the call finder. On the other hand relay R1 is energized and closes its 50 contacts. Over contact 6r1 the starting impulse is given over the start lead AN to the call finder in the known way. At the same time the testing circuit for relay T1 in the call finder is prepared over contacts 7r1 and 8r1. When the call finder 55 tests on the calling line, relay T1 energizes and brings the call finder to rest in the known manner, earth in the group selector, c-wiper of the call finder, contact 7r1, winding II of relay R1, contact 9t1, winding II of relay T1, battery, earth. Relay T1 energizes and first by closing contact 60 10t1 causes the connecting line VL to be switched through to the call finder AS1 and further over contact 11t1 effects the connection of blocking 65 potential to the c-lead of the final selector connection for subscriber TSt2, and also disconnects the high resistance winding I of relay R1 from the a-lead of the speaking line by opening contact 1t1 and closing contact 12t1. Relay R1 holds 70 up, however, over its winding II which occurs 75

in the circuit of relay T1 until the end of the call.

When the call finder has tested on the calling line the potential in the group selector which has been reached is connected to the two speaking leads of the connecting path set up over the call 5 finder AS1. Accordingly a circuit is set up for relay U1 at the switching-over point USt1 and in this circuit the relay energizes: earth, battery, winding I of relay A1 in the group selector, call 10 finder AS1, contact 2t2, a-lead of the connecting 15 line, winding I of relay U1, contact 3u2, subscriber's station TSt1, contact 4u2, winding II of relay U1, contact 5u1, and earth. By closing contact 12u1 relay U1 effects the switching through to the b-lead of the connecting line. 15 Relay U1 thus holds up in the loop to the group selector. The further setting up of the call takes place as for an individual subscriber's call. On release of the connection relays T1 and R1 de-energize so that the switching devices both at 20 the switching over points USt1 and USt2 are returned to the rest position.

Corresponding switching operations take place when a call is initiated from subscriber's station TSt2. If however, station TSt1 is already engaged in a call and station TSt2 then wishes to set up a call this is prevented since after the energizing of relay U1 contacts 13u1 and 14u1 are opened so that station TSt2 is completely disconnected from the connecting line. If, however, subscriber TSt2 is engaged in a call relay U2 is energized and thus station TSt1 is blocked as regards outgoing calls through the opening of contact 3u2 and 4u2, while for station TSt1 incoming calls find the approach to the final 35 selector characterized as being engaged on account of the earth potential connected to the c-lead over contact 15t2.

What is claimed is:

1. In a telephone system, a common connecting 40 line, telephone lines branched from one end of said common line and normally connected thereto, connecting paths branched from the other end of said common line, a switch in each of said connecting paths, controlling means at the junction 45 of said common line and said connecting paths, means responsive to a call from either one of said telephone lines for taking said common line into use and for extending the call over one of said connecting paths to the switch in said path, 50 means for operating the switch of either path to extend the call depending upon the line calling, and means responsive to the extension of the call by a switch for operating said junction controlling means.

2. In a telephone system, a common connecting line, telephone lines branched from one end of said common line and permanently connected thereto, connecting paths branched from the other end of said common line, a switch in each 60 of said connecting paths each for extending calls from said common line, controlling means at the junction of said connecting paths and said common line, means responsive to a call from one of said telephone lines for operating one of said 65 switches to connect with the associated connecting path and extend the call, said controlling means operated simultaneously with the extension of the call from a line to connect the calling telephone line with the connecting path and its 70 associated switch.

3. In a telephone system as claimed in claim 2 in which the connecting switch has access to further switches for extending the call, means for testing said further switch for its busy or idle 75

condition, and means in the event the further switch is idle and the call is extended for operating the junction controlling means.

4. In a telephone system, a common connecting line, telephone lines extending from one end of said common line, connecting paths extending from the other end of said common line, a switch in each connecting path for selecting the same, a further switch connected to said first switch for extending the connection, switching means at the junction of said common line and said connecting paths, means responsive to a call from one of said telephone lines for initiating the operation of one of said switches to engage with the connecting path of the calling line, means for testing the busy or idle condition of said other switch after said first switch is operated, and means responsive to the extension of the connecting path through said first switch for operating the junction switching means.
5. In a telephone system as claimed in claim 4 in which the switching means disconnects the other connecting paths and associated switches from the common line.
6. In a telephone system, a common connecting line, a pair of telephone lines branched from one end of said common line, a pair of connecting paths branched from the other end of said common line, a switch having access to the individual

connecting paths, means responsive to a call from one of said telephone lines for initiating the operation of the switch over a path including one side of said common line and one side of the connecting path, the other of said telephones exercising its call initiation over the other side of the common line and one side of the other connecting path to the other switch, switching means for switching both sides of the common line through to one or the other of said connecting paths, said switch means operated to disconnect the other connecting path responsive to the switching through of the calling connecting path to the switch.

7. In a telephone system as claimed in claim 6 in which the switch comprises a finder switch that searches for the calling connecting path and upon engaging the connecting path tests for an outgoing trunk to extend the call and responsive to the extension of the call through the switch operates the junction switching means to disconnect the other connecting path.

8. In a telephone system as claimed in claim 6 in which after the connecting path is disconnected from the common line by the switching means the disconnected connecting path is guarded from seizure on incoming calls directed to the other telephone line.

FRITZ WOLF.
